United States Patent Office.

NICHOLAS MÜLLER, OF NEW YORK, N. Y.

Design No. 2,920, dated February 4, 1868.

DESIGN FOR A BASE OR STAND.

The Schedule referred to in these Letters Patent and making part of the same.

TO ALL WHOM IT MAY CONCERN:

Be it known that I, NICHOLAS MÜLLER, of the city of New York, and State of New York, have invented a new and original Design for a Base or Stand; and I hereby declare that the following is a full and exact description thereof, which will enable those skilled in the art to make and use the same, reference being had to the accompanying drawings, forming part of this specification, in which drawings—

Figure I is a front elevation of a base or stand containing my design.

Figure II is an outline view of the base or stand, viewing from the top.

Figure III is an outline view of the base along the line *a b* of Fig. I.

This invention consists in a new and original design for a base or stand, as shown in the drawings, the design being composed of ornaments and arabesques, as represented in Fig. I, placed respectively on the front and sides of said base or stand, the whole, combined, forming an ornamental design for a base or stand.

What I claim as my invention, and desire to secure by Letters Patent, is—

The design for a base or stand, represented in the accompanying drawings.

NICHOLAS MÜLLER.
